(57) **CLAIM**

The ornamental design for a vehicle light plug locking system, as shown and described.

DESCRIPTION

FIG. 1 is a front, top perspective view of a vehicle light plug locking system showing our new design;

FIG. 2 is a front elevation view thereof, the rear elevation view being a mirror image thereto;

FIG. 3 is a right side elevation view thereof; a left side elevation view being a mirror image thereto;

FIG. 4 is a top plan view thereof;

FIG. 5 is a front, top perspective view of a modified embodiment of the design of FIGS. 1-4; and,

FIG. 6 is a front elevation view thereof, the rear elevation view being a mirror image thereto.

The broken line portion of the figure drawings is included to show unclaimed subject matter only and forms no part of the claimed design.
